L. D. GROSVENOR.
SEED SHELLER AND THRESHING MACHINE.

No. 8,375.

Patented Sept. 23, 1851.

UNITED STATES PATENT OFFICE.

L. D. GROSVENOR, OF SOUTH GROTON, MASSACHUSETTS.

IMPROVEMENT IN MACHINES FOR STRIPPING SEED FROM BROOM-CORN.

Specification forming part of Letters Patent No. 8,375, dated September 23, 1851.

To all whom it may concern:

Be it known that I, L. D. GROSVENOR, of South Groton, in the county of Middlesex and State of Massachusetts, have invented a new and Improved Machine for Stripping the Seed off the Brush of Broom-Corn, and also for Thrashing Various Kinds of Grain, termed the "Seed-Sheller and Thrashing-Machine;" and I do hereby declare that the following is a full, clear, and exact description of the construction and operation of the same, reference being had to the accompanying drawings, forming part of this specification, in which—

Figure 1 is a top or bird's-eye view. Fig. 2 is a side elevation. Fig. 3 is a side elevation of the working parts, the comb-rollers being omitted. This is the opposite side from Fig. 2. Fig. 4 is a horizontal section taken at the line *x x*, showing a portion of the bearded endless belt and part of the lower or under comb-rollers.

Similar letters of reference indicate corresponding parts in each of the several figures.

The nature of my invention consists in placing obliquely upon a rectangular frame two comb-rollers, one roller being directly over the other, and the combs formed on them by spikes or teeth driven in and around them in a spiral form. An endless bearded belt running longitudinally carries the broom-corn or whatever is to be thrashed along the whole length of the comb-rollers and between them. The grain and straw are laid transversely on the endless bearded belt, and are secured to it by the pressure of a belt running directly over it. The rollers, by their oblique position, catch the extreme end of the broom-corn, &c., first, and as it is carried along by the endless bearded belt, assisted by the spiral comb on the rollers, the grain is entirely stripped from the straw.

To enable others skilled in the art to make and use my invention, I will proceed to describe its construction and operation.

A A A is the frame, and B B the two comb-rollers. These are placed obliquely or diagonally upon the frame, as seen in Fig. 1, and one directly over the other, as seen in Fig. 2.

C C C C represent the teeth forming the comb on the rollers. These teeth are driven in and around the rollers in a spiral form, the direction of the spiral being the same in both rollers, as seen in Fig. 2. In this figure the teeth or the direction of them is represented by dot-

ted red lines in order to prevent confusion. The teeth overlap each other, but by their spiral form on the rollers are prevented from coming in contact.

D D (represented in all the figures) is the endless bearded belt. This runs longitudinally and passes over the pulleys E F, Figs. 2 and 3.

G G are the spikes or teeth attached to it, and which serve to hold the broom-corn or straw as it is pressed down upon the spikes G G by the endless belt H H, (more particularly seen in Figs. 1 and 3,) and which passes over the pulleys I J.

K, Figs. 1 and 2, is an endless screw on the shaft of the lower or under comb roller, which works into a worm-wheel, L, on the shaft of the pulley E. By this means the motion is communicated between the endless bearded belt D D and the rollers B B.

M N are pulleys upon the shafts of the pulleys J E, and by which motion is given to the endless belt H H.

O is a wedge or curve attached to the bed-piece P. The object of the wedge or curve is to raise the "butts" of the broom-corn, or whatever may be upon the bearded belt D D, off the spikes G G. Its position and form will be seen in Fig. 2.

The bed-piece P is for the upper part of the bearded belt D D to rest upon. Its use will be readily seen by referring to Figs. 2 and 3.

R R, Figs. 1 and 2, are pulleys on the ends of the shafts of the comb-rollers B B, and S is a band passing over them, by which motion is given to the upper roller.

T is the driving-pulley. U is a guard, which partially serves to keep the butts of the broom-corn or straw down upon the spikes of the bearded belt, and thus prevents an undue tax upon the endless belt H H. It also acts as a guide to the bearded belt D D. It may be faced with a metal strip to prevent abrasion.

V is an inclined plane, upon which the broom-corn, or whatever is to be thrashed, is placed transversely, as indicated by the red arrows, Fig. 1. The spikes G G pass through a slot, W, after going over the pulley F.

Operation: Motion being communicated to the machine by means of the driving-pulley T, the comb-rollers B B, the endless bearded belt D D and endless belt H H move in the direction indicated by the black arrows. The spikes G G on the endless belts D D, after passing

over the pulley F, pass through the slot W, which is cut through the inclined plane or feed-board W', catching the butts of the broom-corn, for instance, which is placed transversely upon it, and drawing them under the endless belt H H, said belt pressing the butts firmly upon the spikes G G. The bearded belt D D thus carries the broom-corn along till it is caught at the ends between the comb-rollers B B. The teeth C C C C, forming a spiral on the rollers, serve to force the broom-corn along in the same direction as the bearded belt D D moves, and the teeth C C C C of one roller overlapping those of the other forces or cuts the seed completely off the brush.

By referring to Fig. 1 it will be seen that as the bearded belt carries the broom-corn along between the rollers B B the seed is taken off nearer the butts, owing to the diagonal position of the rollers, and when the broom-corn reaches the extreme end of the rollers the teeth C C C C reach the ends of the brush where it is united to the quill, (see Fig. 4,) thus entirely separating the seed from the brush. The red arrows in Fig. 1 will give a good idea of this, the feathered part representing the butt and the barb on the end of the brush.

By referring to Figs. 2 and 3 the use of the wedge or curve O will be apparent, as the bearded belt D D passes round the pulley E. The wedge or curve O forces the butts of the broom-corn off the spikes G G, as it projects

some distance beyond the periphery of the pulley.

It must be borne in mind that the endless belt H H is not directly over the spikes, but is placed a little on one side, so as not to be pierced by them. (See Fig. 1.)

The straw is not injured or broken by thrashing with this machine, and the work is done quickly and well. For broom-corn I prefer the spikes G G on the belt D D, as represented and described; but for other purposes I consider "lugs" preferable.

Broom-corn may also be evened by this machine in the most perfect manner, the butts being cut off at equal lengths by shears which were formerly patented by me.

Having thus described the nature and operation of my invention, what I claim as new, and desire to secure by Letters Patent, is—

The endless bearded belt D D, constructed of any proper material and having lugs or spikes G G, as described, in combination with the comb-rollers B B, set diagonally upon the frame A A A, in the manner and for the purposes substantially as set forth.

In testimony whereof I have hereunto signed my name, before two subscribing witnesses, this 19th day of March, 1851,

L. D. GROSVENOR.

Witnesses:

H. A. HARTWELL,
JONA. HARTWELL.
